UNITED STATES PATENT OFFICE.

FREDERICK L. HEMMER, OF POUGHKEEPSIE, NEW YORK, ASSIGNOR TO
CHARLES N. ARNOLD, OF SAME PLACE.

NURSERY-CHAIR.

SPECIFICATION forming part of Letters Patent No. 485,382, dated November 1, 1892.

Application filed June 10, 1892. Serial No. 436,260. (No model.)

To all whom it may concern:

Be it known that I, FREDERICK L. HEMMER, a citizen of the United States, residing at Poughkeepsie, in the county of Dutchess and State of New York, have invented certain new and useful Improvements in Chairs; and I do hereby declare the following to be full, clear, and exact description of the invention, such as will enable others skilled in the art to 10 which it appertains to make and use the same.

The invention relates to an improvement in chairs to which a child's table is attached.

It has for its object to provide a chair 15 which will be simple of construction, inexpensive of production, and durable in use.

With these objects in view the invention consists in certain features of construction and combination of parts of the same, which 20 will be hereinafter set forth.

In the drawings, Figure 1 is a perspective view showing a high chair with a movable table attached to it and supported and securely held in place by means of my invention. Fig. 2 is an enlarged side elevation of 25 my device, showing those portions to which it applies detached from the chair. Fig. 3 is an enlarged plan view of the bottom of a detached portion of the chair-seat, better showing my method of locking the table in position; and Fig. 4 is a similar view of the top 30 of a detached portion of the chair, better showing the slot in the chair-arm and the position in the slot of the supporting-pin of the 35 table-arm.

Similar letters refer to similar parts throughout the several views.

A represents those portions of the ordinary frame of an infant's high chair which are 40 not affected by my improvements.

B B' represent the chair-arms, in which are placed the slots I I', preferably rectangular in shape, as shown in Fig. 2, for supporting the removable table C by means of the pins 45 H, projecting inwardly from the upper part of the table-arms D D'. To each side of the chair-seat E are attached the pins F, adapted to engage with a slot G near the lower end of the arms D D'.

50 In order to place the table in position it is

only necessary to drop the arm-pins H into the slots I I', with the table slightly raised above the horizontal position, draw it forward to the position shown in Fig. 2, which brings the pins into secure engagement with the lower arm-slots G, when the table is dropped to its horizontal position ready for use. It will readily be seen that this simple method of adjustment of two sets of pins and the corresponding slots provides without more 60 a firm and solid support for the table against any downward pressure and prevents any danger of displacement while the table is in a horizontal position. In order to lock the table in place, so that the child may not 65 either accidentally or designedly remove it, as often happens with the removable tables hitherto used with infants' chairs, I attach a single spring-catch K to the bottom of one side of E at d, provided with a shoulder e, 70 adapted to abut against the arm D when its slot G is brought into engagement with the pin F. K has a projecting arm b, held in place on E by the staple c, by means of which K may be readily pressed to free its shoulder 75 e from D when it is desired to remove the table from the chair. I do not confine myself to this precise form of a catch, as the objects of my improvements might be attained by any convenient mode of locking my device to 80 prevent its accidental displacement at the lower arm-slot G, and a simple bolt attached to the under side of E in place of the spring-shoulder e would be sufficient for this purpose, though perhaps not so satisfactory; nor 85 do I confine myself to the precise form of arm shown in the drawings, as the great advantage of additional strength and firmness in the support may be secured by the larger leverage of the table-arm secured by placing 90 one of the points of support below the horizontal plane of the chair-arm. D might therefore, instead of being curved, as shown, project backward at an angle from the pin H and have its second point of support farther back on the side of E or even upon the rear vertical side of the chair-frame A; but 95 the shape of the arms and mode of attachment and locking shown are perhaps as strong 100 and convenient as any.

Having thus described my invention, what I claim, and desire to secure by Letters Patent, is—

The combination of a chair having arms containing slots and a seat having pins projecting laterally from the sides thereof with a detachable table having rearward and downward extending arms, said table-arms having at their upper ends pins co-operating with the slots in the chair-arms and at their lower ends slots co-operating with the pins on the

chair-seat, and a lock carried by the chair-seat to engage the table-arm at a point opposite to the slot therein to hold the table in position for use, substantially as set forth.

In testimony whereof I affix my signature in presence of two witnesses.

FREDERICK L. HEMMER.
